UNITED STATES PATENT OFFICE.

LEILIAN LEMASSENA, OF NEWARK, NEW JERSEY.

PICTURE-BUILDING GAME.

1,143,636.

Specification of Letters Patent. Patented June 22, 1915.

Application filed December 10, 1914. Serial No. 876,390.

To all whom it may concern:

Be it known that I, LEILIAN LEMASSENA, a citizen of the United States, residing at Newark, in the county of Essex and State of New Jersey, have invented certain new and useful Improvements in Picture-Building Games; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in games or toys; and, the present invention, has reference, more particularly, to a novel construction and arrangement of devices adapted to provide a picture building game.

The present invention has for its principal object to provide a novel picture building game comprising a suitable combined background and foreground together with a variety of separate or detached picture elements adapted to be applied to the combined background and foreground either singly or in desired grouped relation to thereby complete a picture, said combined background and foreground being provided with a series of position lines which serve as a guide to the user of the game in applying the detached picture elements to the background and foreground, and which answer the application of such picture elements in proper perspective relation to the background and foreground. The said picture elements are made in different sizes so that the same have different perspective values, and each picture element is marked to correspond with or identify it with the particular position line on the combined background and foreground with which it is to be used. The proper or corresponding picture elements may be arranged on their respective position lines in any desired number or in any desired grouped relation, and may be moved upon or in relation to the background and foreground in any desired relation thereto, so long as its proper relation to its corresponding position line is maintained; consequently it will be apparent that a great variety of pictures may be built or formed, and the picture elements are always maintained in proper perspective relation to the background and fore-

ground notwithstanding the various groupings and combinations obtainable.

Other objects of the present invention, not at this time more particularly enumerated, will be clearly understood from the following detailed description of the said invention.

The said invention consists, primarily, in the novel picture building game apparatus hereinafter set forth; and, furthermore, the invention consists in the several novel arrangements and combinations of the various parts of the same, as well as in the details of the construction of said parts, all of which will be more fully described in the following specification, and then finally embodied in the claim which is appended to and which forms an essential part of said specification.

The invention is clearly illustrated in the accompanying drawings, in which:

Figure 1 is a complete view of a flat or horizontal combined background and foreground provided with the position lines, and showing a group of detached picture elements arranged therewith to form a completed or built picture. Figs. 2, 3, 4 and 5 are views of variously sized detached picture element adapted to be applied to and grouped in any desired group relation upon said background and foreground. Figs. 2^A, 3^A, 4^A and 5^A, are respectively back views of the variously sized detached picture elements shown in Figs. 2, 3, 4 and 5, the same showing means for identifying the same for use upon corresponding position lines of the background and foreground. Fig. 6 is a perspective view of a slightly modified form of combined background and foreground, the said background being disposed in vertical relation to the horizontal foreground, and the detached picture elements arranged in proper relation to their corresponding position lines and in vertical relation to the horizontal foreground. Fig. 7 is a detached view of a supporting rod for aerial picture elements the same being used to support such picture elements in proper relation to the vertical background and horizontal foreground. Fig. 8 is a detached view of an insert strip to be combined with the vertical background to bring the same in proper perspective relation to the horizontal foreground. Fig. 9 is a diagrammatic view illustrating the purpose, use and necessity of the insert strip. Fig. 10 is a

diagrammatic view illustrating the principles upon which the picture building game is based, and showing how the sizes of the various detached picture elements are obtained.

5 Similar characters of reference are employed in all of the hereinabove described views, to indicate corresponding parts.

Referring now to the said drawings, the 10 reference character 1 indicates a flat sheet of cardboard or other desirable material, upon the face of which is illustrated a background portion 2 and at its lower end a foreground portion 3. Inscribed upon said 15 foreground and background are a series of properly predetermined position lines $a-a$, $b-b$, $c-c$, $d-d$, and $e-e$, which serve as guides indicating the proper perspective positions for detached picture elements in 20 placing upon and moving upon said background and foreground the said detached picture elements.

The reference character a' indicates a proper sized detached picture element to be 25 applied to the background and foreground in proper perspective relation thereto by positioning the same anywhere upon its corresponding position line $a-a$.

The reference character b' indicates a 30 proper sized detached picture element to be applied to the background and foreground in proper perspective relation thereto by positioning the same anywhere upon its corresponding position line $b-b$.

35 The reference character c' indicates a proper sized detached picture element to be applied to the background and foreground in proper perspective relation thereto by positioning the same anywhere upon its corresponding position line $c-c$.

40 The reference character e' indicates a proper sized detached picture element to be applied to the background and foreground in proper perspective relation thereto by positioning the same anywhere upon its corresponding position line $e-e$.

45 As shown in Figs. 2^A, 3^A, 4^A and 5^A, a marked tag t is pasted or otherwise secured upon the back of each picture element to 50 indicate with which position line the same may be properly used, thus identifying by a corresponding mark properly sized detached picture elements for use on or in connection with the respective position lines marked 55 $a-a$, $b-b$, $c-c$, $e-e$, etc., as already above set forth. When the picture elements are printed the tag t may be formed as extending from the edge thereof, so that the identifying mark of the same may be printed at 60 the same time as the picture face, subsequently such tag t is cut off and secured to the back of the picture element as shown. It will be apparent that when any of the 65 said detached picture elements are laid flat upon the combined foreground and back-

ground in any position upon their corresponding position line they will immediately fit into the picture in their proper perspective relation thereto, at the same time a wide scope of combined relation and grouping of 70 any desired number of such detached picture elements is obtainable, whereby the picture can be made to express different subjects and episodes in various ways according to the exercise of the imaginative 75 ingenuity of the user of the game. For example, as illustrated in the drawings, the background represents the interior of a circus tent, the foreground the ring or performer's stage, and the detached picture elements represent the performers. It will, of course, be clear that a great variety of performers, animals, clowns, etc., may be represented by the detached picture elements, and that the same may be grouped upon the 80 background and foreground so as to represent a great variety of circus acts and episodes. The detached picture elements may be furnished in sets, each set representing some circus feature, and the separate figures 85 of each set may be of different sizes to provide different perspective values when grouped together upon the background and foreground in proper relation to their corresponding position lines. It will also be seen 90 that the relation of the picture elements, as between themselves, may be changed and changed again by moving the same anywhere upon their respective position lines, while always maintaining the same in correct 95 perspective value or relation to the background and foreground.

100 While I have used the circus subject as illustrative of the principles of my present invention, it will nevertheless be clearly evident, that the principles of my invention may be applied to a wide variety of subjects, and the picture subject of the background and foreground together with detached picture elements for application thereto, may 105 illustrate any subject desired by the designer or manufacturer.

110 Referring now to Fig. 6 of the accompanying drawings, I have illustrated therein a slightly modified construction of my novel 115 picture building game, still embodying, however, the principles of my present invention. In this modified construction I provide a flat sheet 4 of cardboard, or any other suitable material, upon the face of which is 120 illustrated a background portion 5 and at its lower end a foreground portion 6. In this modification the background portion 5 is bent upward to erect the same in a vertical plane, while the foreground portion 6 is 125 maintained in a horizontal plane. The position lines $a-a$, $b-b$, and $c-c$, are provided upon the foreground portion 6, and the detached picture elements a' , b' , c' , etc., corresponding to the position lines are used and 130

grouped on their proper position lines, so as to provide the desired finished effect in the picture, the only difference being that said detached picture elements are erected 5 vertically on such position lines so as to bear the vertical plane relation corresponding to the vertical background, each picture element being provided with brace-member 7 for holding the same in its erect vertical position. Of course as in the main or flat construction of my invention above described, so in this modified construction the position lines determine the correct perspective position of the picture-elements with relation 10 to the background. In this modified construction the aerial picture elements may be supported by means of the rod 8 which pierces through the background far enough to position the aerial figure in the vertical 15 plane of its proper or corresponding position line, as will be apparent from an inspection of Fig. 6 of the drawings. The said rod 8 has the graduations or marks 9 thereon corresponding to and lying in the vertical 20 plane of the position lines of said foreground.

Referring now to Fig. 9 of the drawings the diagram A shows the combined background and foreground with the position 30 lines, as printed for flat use, and the diagram B shows the same as printed for combined horizontal and vertical use. When the latter use of the background and foreground is contemplated, the background is printed 35 slightly above the foreground, leaving a blank-space S, thus permitting the use of the same printing plates. The background is then bent upward on the top line or position line $d-d'$ of the foreground, with the 40 result that the background is so related to the foreground that the loss in perspective by the fore-shortened view of the foreground is corrected, and the background properly positioned so that when the detached picture elements are erected upon 45 the foreground and associated with their corresponding position lines, the same bear the same perspective relation to the background that they do in the horizontal or flat 50 use of the game, and the only difference being that the picture is presented in vertical plane instead of horizontal plane. In order, therefore, to cover the blank-space S, I provide the insert-strip 10, the color scheme of 55 which corresponds to the background scheme and merges therein.

Referring now to Fig. 10 of the accompanying drawings, I have shown a diagram which is illustrative of the principles upon 60 which the present invention is based. In the said diagram the line A'-B is a base line, and is equivalent to the bottom of the picture background and foreground in my novel game in which nothing is visible below said base-line or picture bottom line.

The line E-E represents the level of the observer's or player's eyes, and is also in the horizontal plane of the horizon, which in perspective is always opposite or in line with the level of the observer's eyes. The line 70 A-X is a position line such as is inscribed upon the picture background and foreground as a guide for the application of the detached picture elements thereto, this position line A-X being below the level of the 75 observer's eye and consequently below the horizon. A²-X² is a similar position line above the level of the observer's eyes and the horizon and of the same distance therefrom as is the line A-X. 80

Now in measuring the height of any figure within the observer's view perspective, the distance between the base-line A'-B vertically to the level of the observer's eyes E-E is averaged for perspective purposes 85 at five feet, this being the standard of measurement, hence the vertical line A'-E in the diagram represents an actual height of five feet, (the scale of the diagram being three-fourths of an inch to the foot). The vertical 90 line A'-D represents a figure having an actual height of four feet, if the same was positioned beside the observer on the base line A'-B. The oblique line A'-P is a measuring line starting from the base line 95 A'-B, at the foot of the four foot figure represented by the line A'-D, to a point opposite to and on a level with the observer's eyes, or in other words on the horizon, since the latter is always opposite the level of the 100 observer's eyes. The oblique line D-P is a similar measuring line starting from the top of the four foot figure, represented by the line A'-D, and extending to a point opposite to and on a level with the observer's 105 eyes, or in other words on the horizon. These measuring lines indicate two parallels extending from the observer to the horizon, but, as is well understood, when viewed perspective and as they recede from the observer they visually or apparently meet at a point on the horizon on a level with the observer's eyes. 110

It is a well known axiom of the rules of perspective that parallels between two 115 parallel lines are equal, as, for example, the rungs of a ladder directly vertical to the observer are equal in length and so appear, and the said rungs will be perspective equal if the ladder is laid upon its side on the ground 120 and extends away from the observer toward the horizon, although as they recede from the observer's position they appear progressively smaller, this being due to foreshortening by distance. Therefore the vertical line 125 Z', extending between a^2-d^2 , erected upon the position line A-X between the measuring lines or parallels A'-P and D-P, indicates the height of the four foot figure when positioned relative to the observer in 130

the foreground position indicated by the line A—X. It will be seen that said line Z' is a line vertically parallel to the line A'—D and represents a figure viewed in perspective or receded from the base line and the observer. While the line A'—D indicates a figure of four feet actual height, the line Z' (a^2-d^2) equals a figure of four feet in height occupying the perspective position of 10 the position line A—X.

Without repeating the above description it will be understood that in the diagram the line J—F represents a figure of four actual feet in height, the lines J—P represent similar measuring lines or perspective parallels, and the line Z' extending therebetween indicates the height of such a four foot figure occupying the perspective position of the position line A²—X², which is above the 15 level of the observer's eyes instead of below, but at the same perspective distance from the observer as the position line A—X, therefore directly above A—X. This position line A²—X², it will be seen, would determine the position of aerial figures in the vertical plane of the perspective or position line A—X.

As indicated by the parallel horizontal lines connecting the tops of the figures or 30 vertical lines Z' with the vertical parallels Z of the same height erected on the respective position lines A—X and A²—X², it will be understood that if the figure represented by the line Z' is moved horizontally anywhere 35 upon either position line A—X or A²—X² it will appear of the same size whether to the right or left of the observer's position, or below the level of the observer's eyes, as when on the line A—X, or above the level 40 of the observer's eyes, as when on the line A²—X².

The above description of said diagram will explain the use of the position lines as 45 shown and inscribed upon the picture background and fore-ground of my novel picture building game, and will explain why the detached picture elements are necessarily identified for use on given position lines rep-

resenting different perspective positions or values, and will further explain why a detached picture element identified for use on a given position line may be placed anywhere upon said line and will always when associated with said line fit into the picture background and foreground in its proper perspective relation thereto, so that a picture while it may be varied as to the position of the detached parts to work out different combinations of completed pictures, yet each completed picture will represent all parts so 60 combined in proper perspective relative to each other.

I am aware that some changes may be made in the arrangements and combinations of the several devices and parts of my present invention without departing from the scope of the same as described in the foregoing specification, and as defined in the claim appended thereto. Hence, I do not limit my invention to the exact arrangements and combinations of the various devices and parts as herein set forth, and as illustrated in the accompanying drawings, nor do I confine myself to the exact details 70 of the construction of the said parts.

I claim:—

In a game of the kind described a picture background having a foreground associated therewith, a series of laterally extending position lines inscribed on said foreground, and various sized, detached, movable and removable picture parts adapted to be applied to said background and foreground, and identified for use on a corresponding position line, so that the same may be moved or 80 positioned anywhere on a corresponding line and be thereby retained in proper perspective relation to said picture background.

In testimony, that I claim the invention set forth above I have hereunto set my hand this 5th day of December, 1914.

LILLIAN LEMASSENA.
